UNITED STATES PATENT OFFICE.

KARL S. HOWARD, OF ST. LOUIS, MISSOURI, ASSIGNOR TO COMMONWEALTH STEEL COMPANY, OF GRANITE CITY, ILLINOIS, A CORPORATION OF NEW JERSEY.

LOCOMOTIVE STRUCTURE.

Application filed August 18, 1936. Serial No. 129,934.

My invention relates to railway rolling stock and consists in an improved locomotive bed structure particularly adapted to be used in a locomotive which includes an internal combustion engine utilized to drive the locomotive by means of electric current or hydraulic pressure.

One object of my invention is to provide an integral construction of the locomotive bed and crank case of the engine mounted thereon, whereby the engine may occupy a lower position relative to the bed than heretofore and whereby the crank case may be utilized as a part of the bed to reinforce the same thereby reducing the weight of the parts required and eliminating much of the labor required for assembling separate structures.

Another object of my invention is to adapt the bed constructed as just described for the mounting of a reduction gear housing or a generator or other apparatus used in conjunction with the internal combustion engine.

Another object of my invention is to adapt such a bed for most effectively mounting a driving shaft and particularly a jack shaft extending transversely of the bed and through which the locomotive driving wheels are operated.

These and other detailed objects of my invention are obtained by the structure illustrated in the accompanying drawings forming a part of the specification, in which—

Figure 1 is a side elevation of my improved structure.

Figure 2 is a one-half longitudinal top view of the bed.

Figure 3 is a vertical transverse section taken on line 3—3 of Figure 1.

Figure 4 is a one-half vertical transverse section taken on line 4—4 of Figure 1.

The bed proper comprises longitudinal sills 1 preferably formed of box cross section and having recesses at intervals whereby pedestal forming portions 2 are provided for the driving wheels 3.

At the ends of the bed the depth of sills 1 may be decreased as the vertical loads are not as great at these points and the sills 1 merge with end sills 4 there being integral elements 5 formed with the end sills for mounting the draft element 6. Suitable di-

agonal braces 7 connect the ends of end sills 4 with the longitudinal sills 1 at points 55 spaced from the end sills.

Throughout a substantial portion of the length of the underframe the sills 1 are connected by a transverse web 8 which is curved downwardly from each sill toward the center of the bed and forms the lower portion of the crank case of an internal combustion engine. The central portion of transverse member 8 is preferably depressed as indicated at 9 to provide a sump for collecting sediment and draining the oil from the crank case. At intervals vertical transverse webs 10 connect sills 1 and have formed in their upper edges integral bearing elements 11 for the engine crank shaft 12. The upper portion 13 of the crank case and the cylinder block 14 are also preferably formed integral with sills 1 although if desired these parts may be made separately and joined to the sills 1, the upper faces of the latter being 75 machined accordingly.

At the right hand end of the internal combustion engine E, I show a compressor C mounted on the sills 1 which are provided with suitable finished bosses 15 for the compressor bracket 16 and to the right of the compressor C the sills 1 are depressed as indicated at 17 to form a lowered mounting for the reduction gear housing H or for other apparatus such, for instance, as a generator 80 or motor which would be used in an electric locomotive. The portion of each sill below the housing H may be reduced in depth because this part of the sill is not recessed to form pedestals for the drivers. These 85 parts of the sills are provided with lateral extensions 18 which provide bearings for a jack shaft 19 extending transversely of the bed through openings in sills 1 and mounting gears 20 on its outer ends. These gears are 90 driven by pinions 21 journaled on the housing H and driven by the mechanism contained therein. The gears 20 are connected to the driving wheels 3 by the connecting rods 22 and the outwardly extending brackets 18 95 provide bearings for the jack shaft in the plane of the driving wheels and shorten the leverage on the jack shaft.

Preferably the lower portions of the sills 1 are provided with integral brackets 23 100 for pivotally mounting the frames of the

two-wheel trucks 24 located under the ends of the locomotive.

Various modifications in the details of my invention such as the number of driving 5 wheels and the particular arrangement and relative location of the jack shaft bearing and other elements described may be made without departing from the spirit of my invention and I contemplate the exclusive use of such 10 modifications as fall within the scope of my claims.

Reference is here made to the locomotive structure shown in my copending applications Serial Numbers 129,932, 129,933, and 15 129,935, each directed to locomotive structures in which the beds or underframes have elements of the driving mechanism formed integrally herewith.

I claim:

20 1. A one piece casting forming a locomotive bed and including parallel sills, and an engine crank case member extending between said sills and forming a longitudinal and transverse brace therefore below the tops 25 of said sills.

2. A one piece casting forming a locomotive bed and including parallel sills, and an engine crank case member extending between said sills and forming a brace therefore below the tops of said sills, said member 30 having an oil sump integral therewith.

3. A one piece casting forming a locomotive bed and including parallel sills, and an engine crank case member parallel with and 35 extending between said sills and forming a brace therefore below the tops of said sills, said member having crank shaft bearings integral therewith and disposed longitudinally of the bed.

40 4. A one piece casting forming a locomotive bed and including parallel sills, and an engine crank case member extending between said sills and forming a brace therefore below the tops of said sills, said member having 45 an oil sump and crank shaft bearings integral therewith.

5. A locomotive bed comprising longitudinal side members each having pedestal forming recesses, said side members being 50 depressed beyond the end pedestal portions to provide a lowered mounting for a reduction gear housing, and motor structure formed integrally with said members.

6. A one-piece locomotive bed comprising 55 longitudinal side members each having pedestal forming recesses, said side members having aligned integral bearings for a jack shaft located outside the plane of the pedestal portions.

60 7. A one-piece locomotive bed comprising longitudinal side members each having pedestal forming recesses, each of said side members having integral bearings for a jack shaft located outside of the plane of its 65 pedestal portions.

8. In a locomotive bed, parallel sills, integral transverse members bracing said sills and forming engine crank shaft bearings substantially at the level of the tops of said sills, said sills being depressed beyond said 70 bearing forming portions to provide a mounting for a gear reduction housing with its base below the level of said bearings.

9. In a locomotive bed, parallel sills, integral transverse members bracing said sills and forming engine crank shaft bearings substantially at the level of the tops of said sills, said sills being depressed beyond said bearing forming portions, said depressed portion including integral bearings for a jack 80 shaft extending transversely of the bed.

10. In a locomotive bed, parallel sills, integral transverse members bracing said sills and forming engine crank shaft bearings substantially at the level of the tops of said sills, said sills being depressed beyond said bearing forming portions to provide a mounting for a gear reduction housing with its base below the level of said bearings, there being integral 85 bearings below said mounting for a transverse jack shaft.

11. A one piece casting forming a locomotive bed and comprising box shaped side sills with integral transverse members forming the lower portion of the crank case of an internal 90 combustion engine.

12. A one piece casting forming a locomotive bed and comprising box shaped side sills with integral transverse members forming the lower portion of the crank case of an internal 100 combustion engine, there being outwardly extending projections on said sills forming jack shaft bearings in the same plane as the locomotive wheels.

13. In a locomotive bed having longitudinal sills, an internal combustion engine cylinder block formed integrally with the sills.

14. In a locomotive bed having longitudinal sills, an internal combustion engine crank case and cylinder block formed integrally 110 with the sills.

15. A one piece casting comprising a locomotive bed having an internal combustion engine crank case and cylinder block formed integrally therewith.

16. A one piece casting forming a locomotive bed and the lower portion of the longitudinally extending crank case of an internal combustion engine and also forming transversely extending bearings for shafting 120 through which said engine operates the locomotive driving wheels.

17. In a one piece casting longitudinal sill members and transverse bracing members forming a locomotive bed, there being integral extensions on some of said members forming bearings for driving shafts for the locomotive driving wheels.

18. In a locomotive bed, parallel sills and an engine crank case integral with and paral- 130

leling said sills and positioned between them below their tops and bracing them transversely of the bed substantially throughout the length of the crank case.

5 19. A one-piece casting forming a locomotive bed and a lower portion of a crank case of an internal combustion engine and provided with longitudinally disposed crank shaft bearings for said engine and provided 10 with transversely disposed bearings for a jack shaft by which the engine is operatively connected to the locomotive driving wheels.

20. A locomotive bed having an internal combustion engine crank case and cylinder block formed integrally therewith.

21. A locomotive bed having an internal combustion engine crank case, crank shaft bearings and cylinder block formed integrally therewith.

20 22. A one-piece casting including a locomotive frame sill, a driver pedestal, and an internal combustion engine crank case extending longitudinally of said sill, all formed integrally.

25 23. A one-piece casting including a locomotive frame sill, a driver pedestal, an internal combustion engine crank case extending lon-

gitudinally of said sill, and an engine cylinder block, all formed integrally.

24. A one-piece casting including a locomotive frame sill, a driver pedestal, an internal combustion engine crank case extending longitudinally of said sill, and crank shaft bearings, all formed integrally. 30

25. A one-piece casting including a locomotive frame sill, a driver pedestal, an internal combustion engine crank case extending longitudinally of said sill, crank shaft bearings, and an engine cylinder block, all formed integrally. 35

26. A one-piece casting comprising a locomotive bed having driver pedestals and the crank case of an internal combustion engine formed integrally therewith and extending longitudinally thereof. 40

27. A one-piece casting comprising a locomotive bed having driver pedestals and the crank case of an internal combustion engine, and crank shaft bearings formed integrally therewith and extending longitudinally 50 thereof.

In testimony whereof I hereunto affix my signature this 13th day of August, 1926.

KARL S. HOWARD.
